INVENTOR
Caroline A. Peters

Edmund B. Haase.

ATTORNEY

UNITED STATES PATENT OFFICE.

CAROLINE A. PETERS, OF LOS ANGELES, CALIFORNIA.

HAT.

1,342,132.

Specification of Letters Patent.

Patented June 1, 1920.

Application filed April 28, 1919. Serial No. 293,194.

To all whom it may concern:

Be it known that I, CAROLINE A. PETERS, a citizen of the United States, residing at Los Angeles, in the county of Los Angeles 5 and State of California, have invented new and useful Improvements in Hats, of which the following is a specification.

My invention relates more particularly to that class of women's head gear commonly 10 known to the trade as "sport" hats.

An object of my invention is to provide a "sport" hat construction whose principal members may be readily detached from one another when it is desired to cleanse the 15 same.

A further object of my invention is to provide a novel form of hat construction, in which the several members forming the hat may be detachably secured together, and in 20 which the securing means will be effectually concealed from view when the members are assembled to form a hat.

A still further object of my invention is to provide a "sport" hat construction that is 25 highly ornamental in configuration, and one that will have all the appearances of a hat of usual form.

I accomplish the above objects by means of the construction described herein, and 30 illustrated in the accompanying drawings in which:

Figure 1 is a side elevation of my complete hat in an assembled condition.

Fig. 2 is a central section through my im- 35 proved hat in an assembled condition.

Fig. 3 is a perspective view of the hat brim showing the method of attaching the annular hat band thereto.

Fig. 4 is a perspective view of my hat 40 brim showing the method of suspending the same after laundrying.

Fig. 5 is a plan view of the hat crown in an unfolded position.

Fig. 6 is a longitudinal section through a 45 portion of the hat band.

Fig. 7 is a vertical cross section taken on line 7-7 of Fig. 3.

Fig. 8 is an enlarged cross section taken on line 8-8 of Fig. 1.

Fig. 9 is an enlarged cross sectional per- 50 spective view through the hat brim showing its method of construction.

Referring more specifically to the drawings 10 designates a hat formed of washable fabrics, and consisting of a brim 11,

band 12, and a crown piece 13, all adapted to be detachably assembled to form a hat.

The hat brim 11 in this instance consists of an annular member, frusto-conical in configuration, and preferably formed of inside 60 and outside facings 14 and 15 respectively, a lining 16 of stiffening material being interposed between the facings and the whole stitched together, so as to retain the brim in the desired shape. Secured at intervals 65 along the upper annular edge 17 are a plurality of female snap members 18, and also secured to said edge is a hat lining 19, the lining at the center thereof being provided with a loop 20, for the purpose of suspending 70 the brim for drying after a cleansing operation.

The hat band 12, is preferably formed of a single strip of material of the required length and width, the ends adapted to overlap, and being detachably secured together by means of snap fasteners 21, the strip or band being provided with a lining having a plurality of small "bones" 22 transversely disposed and secured thereto at intervals 75 along the band for the purpose of maintaining said band in a vertical position when attached to the hat brim. The inner face of said band, adjacent the lower edge thereof is provided with a plurality of male snap 80 fastener members adapted to engage the female snap fastener members 18, secured to the outer face of the hat brim 11 as clearly shown in the various figures of the drawing. The outer face of the band 11 adjacent its 85 lower edge is also provided with a plurality of female snap fastener members 23.

The crown piece 13, preferably consists of a circular centrally disposed member 24, which is sewn or otherwise secured to a substantially rectangular member 25, the edges of said member being formed in this instance into a plurality of tabs 26, one for each of its four corners, and the edges of said rectangular member between the corner 95 tabs 26, are formed into shorter or smaller tabs 27, the inside faces of all of said tabs being provided with male snap fastener members 28, which are adapted to engage the female snap members 23 secured to the outer face of the hat band 12. The snap fasteners securely hold the crown piece 13 100 in position on the hat band as clearly shown in Figs. 1 and 2 of the drawing.

The various members of my hat construc- 110

tion may be varied in configuration, and formed of materials of different textures and colors without departing from the spirit of my invention.

5 It will be noted from the above description that I have produced a "sport" hat construction whose various members may be quickly and easily laundered, and when assembled will present a fresh appearance, the 10 constant laundering continually enhancing the beauty of the material of which the hat members are formed.

What I claim is:

A hat construction, comprising an annular brim member formed of outer and inner

strips of a flexible fabric, a stiffening means interposed between said fabric strips, a hat band member formed of two strips of fabric having a stiffening means mounted therebetween, its ends being detachably secured together, said hat band member being detachably secured to said brim member, said hat band member adapted to constitute a form for the hat crown piece, and a flat flexible fabric crown piece detachably secured to the 25 hat band member.

In witness that I claim the foregoing I have hereunto subscribed my name this 31st day of March, 1919.

CAROLINE A. PETERS.
